TOY CUCKOO CLOCK

Albert Stubbmann, Flushing, N.Y., assignor to Kohner Bros., Inc., New York, N.Y., a corporation of New York

Filed Sept. 30, 1963, Ser. No. 76,785

Term of patent 14 years

(Cl. D34—15)

FIG. 1 is a three-quartered perspective view of a toy cuckoo clock showing my new design;

FIG. 2 is a front view of my design; and

FIG. 3 is a right side view of my design.

The dominant features of my invention are shown in full lines. The back of my design is flat and has no ornamental features.

I claim:

The ornamental design for a toy cuckoo clock, substantially as shown and described.
